UNITED STATES PATENT OFFICE.

FRANK H. CONGDON, OF EAST GREENWICH, RHODE ISLAND.

DESIGN FOR A SEPARATOR.

SPECIFICATION forming part of Design No. 28,293, dated February 15, 1898.

Application filed December 14, 1897. Serial No. 661,897. Term of patent 14 years.

To all whom it may concern:

Be it known that I, FRANK H. CONGDON, of East Greenwich, in the county of Kent and State of Rhode Island, have invented and 5 produced a new and original Design for a Separator, of which the following is a full, clear, and exact specification.

Reference is to be had to the accompanying drawings, forming a part of this specification, 10 in which similar characters of reference indicate corresponding parts in both the figures.

Figure 1 is a side elevation of the separator, showing my design; and Fig. 2 is a plan view 15 of the same.

15 The leading feature of my design consists in the sidewise-bent end A' of the blade A.

A minor feature of the design consists of the rib B, beginning at the inner end of the blade A at the usual attaching-bracket and extending along the middle of the face of 20 the blade, diminishing gradually, and finally terminating at the beginning of the curved end A'.

I claim—

The design for a separator, as herein shown 25 and described.

FRANK H. CONGDON.
